L. SIMENOWSKY.
BOTTLE STOPPER.
APPLICATION FILED NOV. 17, 1919.

1,369,477.

Patented Feb. 22, 1921.

UNITED STATES PATENT OFFICE.

LOUIS SIMENOWSKY, OF MILWAUKEE, WISCONSIN.

BOTTLE-STOPPER.

1,369,477.

Specification of Letters Patent. Patented Feb. 22, 1921.

Application filed November 17, 1919. Serial No. 338,538.

To all whom it may concern:

Be it known that I, LOUIS SIMENOWSKY, a citizen of the United States, and resident of Milwaukee, in the county of Milwaukee and State of Wisconsin, have invented certain new and useful Improvements in Bottle-Stoppers; and I do hereby declare that the following is a full, clear, and exact description thereof.

10 My invention relates to new and useful improvements in bottle stoppers, more particularly of that type including a plug member carried by a yoke which is connected with lever arms pivoted to an attaching member secured about the neck of the bottle whereby said yoke member may be shifted upon rocking the lever arms to either compress the plug in the bottle neck or to release the plug for discharge of the contents 20 of the bottle.

It is in general the object of my invention to simplify and otherwise improve the structure and to increase the efficiency of stopper devices of this character. Inasmuch as 25 such stopper devices constitute a considerable item of expense, it is more particularly my object to provide a stopper device which may be detachably associated with the bottle neck, whereby the device may be readily removed upon breakage of the bottle, and applied to another bottle. A more detail object in this connection resides in the provision of an arrangement operable incidental to the application of sealing pressure on the stopper plug for positively locking the attaching member of the stopper device on the bottle neck.

With the above and other objects and advantages in view, which will be apparent 40 as the description proceeds, my invention resides in the novel features of construction, combination and arrangement of parts which will be hereinafter more particularly described and defined by the appended 45 claims.

In the accompanying drawings:

Figure 1 is an elevational view of the bottle neck showing my improved stopper device associated therewith.

50 Fig. 2 is a transverse sectional view on the line 2-2 of Fig. 1.

Fig. 3 is a side elevational view of the attaching member of the device.

55 Referring now more particularly to the accompanying drawings, I have shown a bottle neck A of conventional type pro-

vided with the usual bulge at its upper end which forms a consequent shoulder s adjacent the top thereof.

My improved stopper device comprises an attaching member 5 formed of an elongated strip of sheet metal having considerable resilience and bent into U-shape, with the outer end portions of its legs slightly converged, said attaching member being reinforced by a brace rib 6 longitudinally struck from its intermediate portion and extending from end to end of the strip. This attaching member is adapted to fit snugly about the neck of the bottle immediately below the shoulder s, the resilient grip of the member by reason of the convergence of its legs serving to hold the member in this position. The ends of the legs of the attaching member are provided with upward extensions 7 adapted to engage the bulge when the attaching member is seated against the shoulder. The usual wire lever member 8 is provided, having end portions 9 pivotally connected with the usual yoke 10 carrying the stopper plug 11, and the free terminals of the lever member are inwardly directed to form pivot pintles 12, these pintles being engaged in bearing openings 13 formed in the rib portions of the legs of the attaching member 5. By disposing the bearing openings 13 in the rib 6, the edges of the openings are spaced a considerable distance from the surface of the bottle neck, thus permitting a substantial length of the pivot pintles 12 to pass through the openings and effect a secure pivotal connection.

An exceedingly simple, effective and readily manipulated stopper device has thus been provided. When the yoke 10 is shifted to draw the stopper plug 11 into the bottle neck, the attaching member 5 is held up against the shoulder s of the bottle neck, and the projections 7 of the attaching member abut the bulge of the bottle neck to prevent possible detachment of the stopper device by movement of the attaching member transversely of the bottle neck. When, however, the stopper plug 11 is released, the attaching member 5 may be slid downwardly a slight distance on the bottle neck to dispose the projection 7 below the bulge and the device may be then readily withdrawn from the bottle neck.

What is claimed is:

1. A stopper device of the class described comprising a substantially U-shaped at-

taching member adapted to embrace the neck of a bottle adjacent the bulge thereof, a lever member pivoted to the intermediate portions of the legs of said attaching member, a yoke carried by said lever member, a stopper plug carried by the yoke and upstanding projections on the ends of the legs of the attaching member adapted to engage the bulge of the bottle neck to prevent lateral withdrawal of the attaching member from the bottle neck when the stopper plug is engaged in the bottle neck.

2. A stopper device of the class described comprising an attaching member adapted to fit about the neck of a bottle adjacent the

bulge thereof, said attaching member being formed of an elongated strip of metal bent to desired shape and provided with an outwardly struck reinforcing rib extending longitudinally through its intermediate portion, said rib being provided with bearing openings at opposed portions of the strip and a plug carrying lever having pintle portions engaged in said bearing openings of the rib.

In testimony that I claim the foregoing I have hereunto set my hand at Milwaukee, in the county of Milwaukee and State of Wisconsin.

LOUIS SIMENOWSKY.
